UNITED STATES PATENT OFFICE.

BERT KENNEDY AND LEWIS SAIGER, OF GLOVERSVILLE, NEW YORK.

FLY SHOOTER.

Application filed April 22, 1922. Serial No. 555,999.

To all whom it may concern:

Be it known that we, BERT KENNEDY and LEWIS SAIGER, citizens of the United States, and residents of Gloversville, in the county of Fulton and State of New York, have invented certain new and useful Improvements in Fly Shooters, of which the following is a specification.

This invention relates to a fly shooter.

10 The purpose of the invention is to provide a device of the above character in the form of a pistol and which may be employed to kill flies, or the like, and which is also adapted to serve as means of entertaining 15 children.

It is also within the scope of the objects of the invention that the device be extremely simple in construction and inexpensive to manufacture.

20 Other objects will hereinafter appear.

The invention is illustrated by way of example in the accompanying drawings, in which:—

Figure 1 is a perspective view of the device and showing the striker when in its set position.

Figure 2 is a longitudinal sectional view of the same and illustrating the application of the device for killing a fly.

25 Referring to the drawings more particularly, the pistol consists in a body comprising a handle H formed at its forward end with a stock or barrel B. The body described may be made of any material desired, a light and inexpensive material being preferable. The handle portion may be knurled upon its sides as at 10, and intermediate the handle H and barrel B there is provided a slot 11 which is arranged vertically with respect to the barrel B and handle H and substantially of the size shown. The end walls of the slot may taper toward the lower end thereof as shown in Figure 2. Also at this point the body is formed with a pair of ears 12 which are arcuate in shape, as shown, and one occurring upon each side of the handle or barrel, and the inner surface of each ear being flush with the corresponding side wall of the slot 11.

30 The forward end of the barrel B is recessed to provide the two protrusions or extensions 13 which are preferably of the shape shown in order that the body of the device, as a whole, may be as attractive as possible.

35 Between the extensions 13 there is pivoted

the head portion 14 of a striker S by the means of a pin 14', said striker otherwise consisting in the shank portion 15 which terminates at its other end in a circular plate 16. The striker S may be turned rearwardly upon its pivot 14' to lay upon the upper side or edge of the barrel B, as illustrated in Figure 1.

40 In the slot 11 there is pivoted a trigger member 17 which is crescent in shape and pivotally supported by a pin 18. The upper end portion 19 is adapted to engage with the rear edge of a head or hammer generally indicated by the reference numeral 20, said hammer being pivotally supported by a pin 21 and having its lower end portion 22 curved and pointed as shown, while its upper end is formed with a head 23 and adapted to extend above the barrel B. The 45 head 23 is formed with a forward projection 24 which is adapted to be brought to engage upon the plate 16 of the striker S.

45 The striker S is formed with a transverse opening 25 at a point adjacent its head portion 14 through which there is extended the one end of an elastic loop 26, said loop being secured against movement through the opening 25 of the striker as at 27. The elastic 50 26 is otherwise extended through a transverse bore or opening 28 in the barrel B, and its other end portion looped about the head 23 of the hammer 20 and disposed in a notch 29 of said hammer.

55 In operating the present device, the striker 55 S is turned rearwardly upon its pivot 14' to the position shown in Figure 1 and so held by the head 23 of hammer 20. The elastic 60 26 urges the striker to swing upon its pivot 14', and upon the trigger 17 being manipulated to operate the hammer 20 to move the head 23 of said hammer rearwardly and release the striker S said striker will swing 65 forwardly under tension of the elastic 26 and if brought to strike a fly, or the like, 70 100 may serve to kill the same, as illustrated in Figure 2.

75 While we have shown and described the preferred form of our invention, we wish it to be understood that we are aware of the 80 fact that the construction, combination and arrangement of parts may be changed by those skilled in the art without departing from the spirit of the invention as indicated by the appended claims.

85 We claim:—

90 1. A pistol of the character described,

- comprising a stock including a handle therefor, a striker comprising a shank having a plate formed at its one end, means for pivoting the other end of said striker to the forward end of the stock whereby said striker may be folded backward upon the stock, a hammer for engaging the striker and holding it in its rear swinging position, trigger means for operating the hammer to release the striker, and an elastic having its one end connected to the striker at a point adjacent its pivoted end, and its other end connected to the hammer and adapted to forcibly swing the striker forwardly upon its pivot when released from said hammer.
2. A pistol of the character described, comprising a stock including a handle at one end thereof, a striker having its one end pivoted to the forward end of said stock and adapted to swing forwardly with relation to said stock, an elastic having its one end connected to the pivoted end of said striker and then passing upon the under side of said stock and upwardly through an opening in the stock, a hammer positioned at the rear end of said stock and having the other end of said elastic secured thereto whereby to urge the same forwardly for engaging the striker when said striker is swung rearwardly against the tension of said elastic, and a trigger for operating the hammer to release said striker.
3. A pistol of the character described, comprising a stock provided at its one end with a handle and having its other end bifurcated, a striker consisting in an elongated member having its one end pivoted between the prongs afforded by the bifurcated ends of said stock, a hammer pivotally mounted at the rear end of the stock, an elastic connected to the pivoted end of said striker and extended rearwardly and connected to said hammer whereby to urge the hammer forwardly, a head upon said hammer adapted to engage and hold the striker in a rearward swung position and against the tension of the elastic, and a trigger adapted to move the hammer for releasing said striker.
4. A pistol of the character described, comprising a stock having at one end a handle, an elongated striker pivotally connected adjacent its one end to the free end of said stock and adapted to be folded or swung rearwardly and upon the upper edge of the stock, a hammer pivotally supported at the rear end of the stock and adapted to be brought to engage upon the associated end of the stock when the same is in its rearward swung position, an elastic having its one end connected to the pivoted end of said striker and then passing partially about said striker and beneath the stock and then upwardly through an opening in the stock and its other end connected to the hammer, and trigger means for moving the hammer to release said striker.
5. A pistol of the character described, comprising a stock having at one end a handle, an elongated striker pivotally connected adjacent its one end to the free end of said stock and adapted to be folded or swung rearwardly and upon the upper edge of the stock, a hammer pivotally supported at the rear end of the stock and adapted to be brought to engage upon the associated end of the stock when the same is in its rearward swung position, an elastic having its one end connected to the pivoted end of said striker and then passing partially about said striker and beneath the stock and then upwardly through an opening in the stock and its other end connected to the hammer, and trigger means for moving the hammer to release said striker.
6. A pistol of the character described, comprising a stock having a handle at one end, an elongated striker having its one end pivotally supported for forward and rearward swinging movement at the forward end of the stock, a hammer pivoted at the rear end of the stock and adapted for engaging the striker when said striker is swung rearwardly upon the stock, an elastic connected to the striker at its pivoted end and passing partially about the pivoted end thereof and then having its other end connected to the hammer whereby to urge the striker to swing forwardly and also retain the hammer in engagement with the striker, and a trigger for operating the hammer to release the striker.

LEWIS SAIGER.
BERT KENNEDY.
